(57) **CLAIM**

The ornamental design for a layout track as shown and described.

DESCRIPTION

FIG. 1 is a top perspective view of a layout track, showing our new design;

FIG. 2 is a front elevational view of the layout track of FIG. 1, the rear elevational view being a mirror image thereof; FIG. 3 is a right elevational view of the layout track of FIG. 1, the left elevational view being a mirror image thereof; FIG. 4 is a top plan view of the layout track of FIG. 1; and, FIG. 5 is a bottom plan view of the layout track of FIG. 1. The broken lines in FIGS. 1 and 3 represent portions of the layout track that form no part of the claimed design. The layout track is shown with symbolic breaks in its length and width. The appearance of any portion of the layout track between the break lines forms no part of the claimed design.
